UNITED STATES PATENT OFFICE.

JOSEPH E. HOLVECK, OF PITTSBURGH, PENNSYLVANIA.

VALVE LOADING AND UNLOADING DEVICE.

1,316,794.

Specification of Letters Patent. Patented Sept. 23, 1919.

Application filed August 12, 1918. Serial No. 249,544.

To all whom it may concern:

Be it known that I, JOSEPH E. HOLVECK, a citizen of the United States, and a resident of Pittsburgh, in the county of Allegheny 5 and State of Pennsylvania, have made a new and useful Invention in Valve Loading and Unloading Devices, of which the following is a specification.

This invention relates to unloading devices and more particularly to devices for unloading and loading a pump or other fluid translating device having suction and discharge valves and a reciprocating plunger or piston for translating fluid from one 10 point to a point of higher pressure through the agency of the suction valves thereof. In the use of high pressure pumps such as those used for pumping water into hydraulic accumulators it is now common practice to 15 drive the pumps, which are usually of the multiple cylinder type although not necessarily so, by means of direct connected electric motors. These motors are usually run continuously and when the necessity for operating the pump ceases instead of stopping the motor it is customary to unload the pump 20 by opening the suction valve thereof and holding the same open for a certain time.

In the operation of a number of hydraulic 25 presses for shaping metal such as shell blanks a number of such presses may be fed from one hydraulic accumulator in which the pressure for example is maintained at twenty-five hundred pounds per square inch. 30 A hydraulic pump is used for charging the accumulator and when the accumulator reaches its uppermost or charged position the pump is unloaded until such time as it is necessary to again charge the accumulator 35 and this time will be dependent upon the manner of operating the presses fed by the accumulator therefore I term the service intermittent service. It may be necessary to charge the accumulator at times very often 40 and at other times not so often and since the starting torque is high and the time required long if the motor driving the pump is stopped and started whenever it is necessary to operate the pump it is found advisable 45 and is now common to operate the pump continuously during the operation of the presses and the accumulator.

An object of this invention is to provide means for automatically loading and unloading the pump in such manner that the torque 50 on the pump crank shaft and therefore on

the motor is thrown on gradually starting at zero torque and gradually increasing to maximum torque.

A further object is to provide a device for 60 automatically unloading the pump when the demand for pressure ceases and for again loading the pump at the beginning of the compression stroke thereof.

This, as well as other objects which will 65 readily appear to those skilled in this particular art, I attain in the device described in the specification and illustrated in the drawings accompanying the same and forming a part of this application. 70

In the drawings Figure 1 is a more or less diagrammatic view partially in elevation and partially in section of a device embodying this invention and Figs. 2, 3 and 4 are diagrams showing the relation of the loading 75 cams of the device and the pump plungers in a multiple cylinder pump of the triplex type.

Since one skilled in this art will understand this invention, a complete pump has 80 not been shown neither has the accumulator or other device into which the pump discharges since this would only complicate the application.

In describing this invention it is assumed 85 that 5 represents one suction chamber of a multiple cylinder pump having reciprocating plungers connected to a crank shaft and that 6 is the suction pipe for supplying the cylinders with water or other liquid or fluid 90 derived from any suitable source. Inlet port 7 of the suction chamber is controlled by means of a suction inlet valve 8 yielding held to its seat by means of gravity and a spring 9. Normally, suction valve 8 95 rises during the suction strokes to admit water to the plunger chamber supplied thereby and will close at the end of the suction stroke and during said stroke be held closed by the pressure exerted by the plunger. 100

A stem 10 axially aligned with suction valve 8 is reciprocable within a guide 11 and through a stuffing box 12 provided in the lower part of the suction pipe 6. The stem is weighted as by means of weights 13 for 105 normally holding it out of contact with the suction valve and a bell-crank lever having arms 14 and 15 is provided for raising said stem and said suction valve to unload the plunger when the demand for water has 110 ceased.

A shaft 16 is connected up to the accumu-

lator or other device to be supplied with water under pressure from the pump, by means of any suitable connections either mechanical or hydraulic and by the same is caused to 5 reciprocate in the direction of arrow A when the demand for water ceases and in the opposite direction when the demand is renewed. The lower end of arm 14 of the bell-crank lever lies between two posts 17 and 18 carried by said shaft and when the shaft is 10 moved in the direction of arrow A the bell-crank is swung and stem 10 is raised in contact with valve 8 thereby raising said valve through the medium of a coiled spring 19 positioned between the lower end member 20 15 of stem 10 and the upper end member 21 of a stem 22 slidable within a guide 23 provided for that purpose. The outer end of arm 15 of said bell-crank is bifurcated and 20 straddles stem 22.

Spring 19 is interposed in the combined stem made up of stems 10 and 22 in order that undue strains will not be put upon stem 10 or valve 8 by the action of the bell- 25 crank during compression strokes of the plunger. If the demand for water ceases during a compression stroke spring 19 will be compressed by the bell-crank and the pressure will be transmitted to valve 8 by 30 means of stem 10 so that said valve will open immediately upon the commencement of the suction stroke of the plunger; spring 19 when fully compressed by the bell-crank not being sufficient to raise valve 8 against the 35 compression pressure.

In order that suction valve 8 may not close to load the pump during compression strokes a continuously rotating cam member 24 is provided. This cam is feathered to 40 shaft 25 and is moved lengthwise of said shaft by means of an actuator 26 mounted on and carried by reciprocating shaft 16. Clearance space is left between the actuator arms and the side face of cam 24 so that 45 the cam may at times be moved independently of the actuator. Shaft 25 by means of gears 29 and 30 is caused to rotate synchronously with the pump crank shaft since shaft 28 is connected up to the crank shaft. 50 Cam member 24 is provided with a circular surface 31 upon which the lower end of stem 22 is adapted to ride when released from its raised position by the bell-crank during the compression strokes of the plunger. The timing of the cam is such that 55 as soon as the end of the compression stroke is reached point 32 of the circular surface 31 will pass under the end of stem 22 and allow the stem to drop thus releasing suction valve 8 to become operative. Cam member 24 is provided with an inclined face 60 65 33 which becomes operative during the operation of the cam member after the stem 22 has dropped to its lowermost position. The inclined face 33 bearing against the side of

the stem forces the cam member along shaft 25 and out of position; such movement is independent of the movement of actuator 26.

Figs. 2, 3 and 4 are diagrams illustrating the relation between the cam members 24 and 70 the crank shaft in a three plunger pump, the position of the crank and cam in Fig. 2 having been arbitrarily chosen. These three figures may also represent different positions of the crank and cam in a single plunger 75 pump. The shape of the cam may be modified from the shape shown so long as stem 22 is allowed to drop only during the suction strokes of the plunger, thus causing the torque to be exerted gradually from zero 80 at the beginning of the compression stroke to maximum. The mechanism is so timed that the bell-crank will lift stem 22 so as to clear cam member 24 before the cam member is moved to a position in line with said stem. 85

It will be understood that this invention is applicable to various types of pumps and in fact to any having suction inlet valves and a plunger or plungers.

In accordance with the provisions of the 90 patent statutes I have described the principle of operation of my invention, together with the device which I now consider to represent the best embodiment thereof, but I desire to have it understood that the device shown is only illustrative and that the 95 invention can be carried out in other ways.

Having thus described my invention what I claim is—

1. In combination with a pump, mechanism actuated at various points in the pump cycle to interrupt delivery of said pump and means operated by said pump for preventing the resumption of delivery at any other point in the pump cycle than the beginning 105 of a discharge stroke.

2. In a pump, means for unloading the pump, said means being adapted to cease functioning at various points in the pump cycle, and means operated synchronously 110 with said pump to prevent reloading said pump except at the beginning of a discharge stroke.

3. In combination with a pump, means automatically controlled by the pressure 115 maintained by said pump for automatically unloading said pump and means operating synchronously with said pump to prevent reloading of said pump except at the beginning of a discharge stroke subsequent to 120 cessation of the functioning of said pressure controlled means, and independently of the cyclic point of said cessation.

4. In a pump, mechanism automatically 125 interrupting delivery by the pump plunger, said mechanism automatically ceasing to function at varying points in the pump cycle, and means operating, when said mechanism ceases to function during a discharge stroke of said pump, to prevent resumption of the 130

pump's delivery except at the beginning of a subsequent discharge stroke.

5. In a pump, a plunger, an intake valve adapted to open to permit charging of said pump and to close to permit discharging of said pump, mechanism controlled independently of said pump to hold said valve open, and means operated by said pump when said mechanism is released during a discharge stroke of said plunger to prevent said valve from closing until said plunger has completed said discharge stroke.

6. In a pump, a plurality of cylinders, respective plungers therefor, means for unloading all of said plungers, and mechanism automatically preventing reloading of said plungers, when said means is rendered inop-

erative, except at a predetermined point in the stroke of each plunger.

7. In a multicylinder pump, a plunger for each cylinder, an inlet valve for each cylinder adapted to close to permit discharge of their respective cylinders, means for opening all of said valves and means automatically preventing subsequent closure of said valves when said opening means is not functioning except at a predetermined point in the stroke of the plunger loaded by each valve.

In testimony whereof I have hereunto subscribed my name this 8th day of August, 1918.

JOSEPH E. HOLVECK.
